UNITED STATES PATENT OFFICE

MARY UDELL SILL, OF BALTIMORE, MARYLAND

DESIGN FOR A CLOCK

Application filed November 18, 1932. Serial No. 46,057. Term of patent 7 years.

To all whom it may concern:

Be it known that I, MARY UDELL SILL, a citizen of the United States, residing at Baltimore, in the State of Maryland, have invented a new, original, and ornamental Design for Clocks, of which the following is a specification, reference being had to the accompanying drawing, forming part thereof.

The figure is a perspective view of a clock, showing my new design.

The arms preferably project through slots in the sides of the casing, and are pivotally mounted inside thereof so that they may be adjusted to different angular positions.

I claim:

The ornamental design for a clock as shown and described.

Baltimore, Maryland, November, 1932.

MARY UDELL SILL,
